LINER PACKING

Marcus M. Cunningham and Lawrence D. Barner,
Houston, Tex., assignors to Barcunshell Corporation,
a corporation of Texas

Application March 7, 1939, Serial No. 260,262

4 Claims. (Cl. 309—3)

This invention relates to cylinders and liners therefor and more particularly to means for effecting and maintaining a fluid tight seal between the liner and surrounding cylinder.

It is a general object of the invention to provide an efficient seal between a cylinder and a removable liner placed therein.

A further object is to provide a cylinder-to-liner seal by providing an expansible element between the cylinder and liner.

Another object is to provide a cylinder and liner with interior annular chamber to receive an expansible packer element to which connection is made with the exterior of the cylinder so that expansive pressure may be applied and maintained.

Still another object is to provide a construction which is especially suitable for mud pumps such as are used for oil field drilling by the rotary method and which includes means for indicating at all times the sealing pressure that is applied between the liner and the cylinder of the pump.

Still another object is to provide the combination of a counterbored cylinder and a flanged liner to provide an annular space therebetween, an expansible sealing element being expanded within such chamber thru pressure applying means which is located exteriorly of the cylinder.

With the foregoing as primary objects other and further objects will be apparent from the following description taken in connection with the drawing in which:

Fig. 1 is an elevational view of a mud pump partly in cross section illustrating an embodiment of the invention as utilized in a pump of this type.

Figs. 2 and 4 are fragmentary sectional views illustrating the utilization of modified forms of an expansible sealing element in accordance with the invention.

Fig. 3 is also a fragmentary sectional view illustrating a modified form of expansible sealing element together with a modification of the mechanism for maintaining a constant expansive force upon such element.

The invention as illustrated in Fig. 1 is incorporated in a mud pump comprising a cylinder 1 provided with a replaceable liner secured in place therein by means of clamping mechanism generally indicated as 3. Within the liner 2 there is provided a suitable piston 4 which is reciprocated therein by means of the piston rod 5 which extends outwardly thru the packing gland 6 at the end of the cylinder. Reciprocation of the piston 4 is instrumental in cooperation with intake valves (not shown) in forcing fluid thru exhaust valves 10 within exhaust valve housings 11 whence such fluid is discharged thru a manifold

12 to the point where the flow of the pumped fluid is desired.

The cylinder 1 is provided with spaced inwardly extending annular flanges 15 and 16 which slidably receive the liner 2. It is impossible to obtain sufficiently intimate contact between the liner 2 and these annular flanges to effect the necessary seal between the cylinder and liner. It is therefore necessary to provide a construction 10 that will prevent the passage of fluid between the liner and cylinder. Such construction is an important feature of the present invention and comprises the provision of a counterbore 20. The liner 2 is provided with an annular flange 21 15 which is adapted to enter this counterbore whereby there is formed an annular chamber between the cylinder and the liner.

In spaced relation with the flange 21 the periphery of the liner 2 is threaded at 23 to receive 20 a ring 24 to form a second annular flange and provide the annular chamber to receive a hollow expansible packing element 25. This element as shown in Fig. 1 has an annular internal chamber 26 and is provided with a thickened end wall 27 thru which a conduit or tube 28 passes. This conduit sealably passes thru the wall of the packing element 25 so that a pressure applied to the interior of the conduit will tend to expand the packing element.

30 When the element 25 is positioned upon the liner 2 the conduit 28 is passed thru an opening 29 in the flange 21 and extends outwardly therefrom. The ring 24 is then positioned upon the liner preliminary to the insertion of the liner 35 assembly within the cylinder.

After the liner assembly has been placed within the cylinder 1 the conduit 28 is passed outwardly thru the drain opening 30 in the cylinder. The usual drain plug is replaced by a plug 31 having a packing gland 32 so as to form a seal about the conduit 28.

40 Mounted at any suitable point upon the pump or elsewhere upon an instrument panel is a pressure applying and indicating mechanism generally indicated at 35. This mechanism comprises a chamber 36 which is adapted to serve as a reservoir for liquid which is applied thru the conduit 28 to the interior of the packing element 25. 45 Above the liquid within the chamber 36 is an air chamber 37 whereby resilient pressure is applied to the liquid therein. A pressure gauge 38 indicates at all times the amount of pressure that is applied to expand the packing ring 25. If it is desired at any time to increase the pressure within the chamber 37 or to add liquid to the chamber, suitable pump means may be attached to the valve cap 39 for such purpose.

It is believed apparent that with a construction just described it is possible to maintain a

desired sealing pressure within the packing element and that any departure from such pressure will be immediately detected by a change in reading in the pressure indicating instrument 38. This feature is of importance as destructive effects by leakage will very quickly require a replacement of the liner 2, if not of the entire pump cylinder and liner.

The mechanism 35 as shown in the drawing is also provided with a conduit 28 which leads to the other cylinder of the pair of cylinders comprising a pump of the type described. By means of this construction a drop in pressure is indicated by both of the gauges 38 and 38' and will indicate that one or the other of the cylinders of the pump is leaking. By manipulation of the valve in the conduits, it is possible to immediately localize the cylinder which is leaking, whereupon the pump unit may be shut down and repair thereof quickly made.

In Fig. 2 there is shown an alternative construction wherein the expansible packing element 25 is provided with an outwardly extending opening 40 which is placed in mating relation with opening 41 in the cylinder 1. In this embodiment the conduit 28 is connected to the opening 41 by means of packing gland 42.

It will be noted that in accordance with this embodiment the packing element 25 is provided with lips 43 adjacent the opening 40 so that internal pressure within the annular chamber 44 will cause effective sealing with the adjacent surface of the cylinder 2.

In the embodiment illustrated in Fig. 3 the packing element 25 is provided with an inner annular opening 50 between flexible annular lips 51. In this embodiment the conduit 28 terminates in the area between the lips 51 whereby internal pressure may be applied to the interior of the packing element. In this embodiment there is also shown a modified form of mechanism for applying pressure thru the conduit 28 to the packing element. This mechanism comprises a cylinder 52 provided with a piston 53 which is urged resiliently downwardly within the cylinder by means of a compression spring 54. A second piston 55 is connected to a threaded stem 56 passing thru the cap 57 in the cylinder. By means of this construction any suitable force may be exerted upon the piston 53 to produce an expansive force within the packing element 25. This force will be indicated by the pressure responsive instrument 60 connected in the conduit 28.

Fig. 4 is illustrative of a construction in which the flange 24' is made integral with the liner 2. When such construction is used the packing element 25 is flexed sufficiently to pass over one of the flanges 21 or 24 to the annular space therebetween.

The embodiment of Fig. 4 is of such construction that the packing element 25 may be relatively thin in a radial direction. In this construction a hollow projection 65 is provided similar to the thickened portion 27 as seen in Fig. 1. The periphery of this projection fits closely within a conical depression in the adjacent wall and provides a seal therewith. The opening through this projection extends inwardly at 66 into the element 25.

In manufacturing this packing element a rod-like member is placed in the mold to form the opening 66. An annular clearance line is also formed by inserting a strip of material 67 which extends annularly from opposite sides of the rod.

like core member. The strip of material 67 may be any suitable material, such as fabric or other fibrous material, the only requisite being that it form a line of clearance so that pressure applied within the opening 66 will cause desired outward expansion of the packing element. This pressure is applied thru a tube 68 which is sealably secured in place by means of a gland member 69 and packing 70.

While the foregoing description has been directed to the utilization of the invention in connection with the mud pump, it is to be understood that the invention is not confined thereto but may be used in any construction wherein a liner is used and it is desired to prevent leakage past the liner due to difference in pressure at opposite ends thereof.

Broadly the invention comprehends the provision of a construction whereby an efficient seal is effected and maintained between a cylindrical member and a liner placed therein.

What is claimed is:

1. A pump construction comprising a cylinder having a counterbore in one end thereof, a liner for said cylinder, a flange on said liner adapted to enter and engage the bottom of said counterbore, a second flange on said liner in spaced relation with the first mentioned flange and adapted to enter the counterbore whereby an annular chamber is formed intermediate the flanges, a hollow packing element in said chamber, and means extending to the exterior of the cylinder for applying a fluid pressure to the interior of the packing element to effect a seal between the cylinder and liner.

2. A pump construction comprising a cylinder having a counterbore, a liner for said cylinder, a flange on said liner adapted to enter the counterbore, a second flange on said liner in spaced relation with the first mentioned flange and adapted to enter the counterbore whereby an annular chamber is formed intermediate the flanges, means for holding the liner within the cylinder with the flange in engagement with the bottom of the counterbore, an expansible packing ring within the chamber, a conduit extending from the packing element to the exterior of the pump cylinder, and means connected to said conduit for continuously applying fluid pressure to the packing ring to effect a seal between the cylinder and liner.

3. The combination with a pump cylinder and liner having an annular chamber therebetween, of a packing ring within said chamber, said ring comprising a unitary body member having flexible annular flanges extending inwardly from the edges of the body and adapted to bear upon one of the cylindrical surfaces within said chamber, a passageway leading from the surface between said flanges to the exterior of the pump cylinder, and means for applying a pressure fluid to the interior of the packing ring through said passageway.

4. The combination with a pump cylinder and liner having an annular chamber therebetween, of an expansible packing ring within the chamber, a fluid passage from the interior of the ring to the exterior of the cylinder, a chamber connected to said passage, a piston within said chamber and means for resiliently urging said piston longitudinally of the chamber to maintain pressure upon fluid within the chamber and packing ring.
